CLAIM

The ornamental design for a multi-dispenser cassette or the like for dispensing doses of sterilizing liquid, as shown and described.

DESCRIPTION

FIG. 1 is a top, front perspective view of a multi-dispenser cassette or the like for dispensing doses of sterilizing liquid showing our new design;

FIG. 2 is a side elevational view thereof, the opposite side being identical thereto;

FIG. 3 is a top plan view thereof;

FIG. 4 is a front elevational view thereof, the opposite side being identical thereto; and

FIG. 5 is a bottom plan view thereof.
